UNITED STATES PATENT OFFICE

JAMES R. JOHNSTON, OF PHILADELPHIA, PENNSYLVANIA

DEPOSITORY

Application filed February 12, 1927. Serial No. 167,690.

This invention relates to an apparatus by means of which successive bank deposits may be made after regular banking hours, the apparatus being adapted to be placed in the outer wall of a bank building and communicating with a vault located within the bank building.

The principal objects of this invention are to provide a device which will be practically fool proof, and to provide a greater amount of security in the completion of the depositing operation after the deposit has been initially placed within the depository.

Other objects and the details of construction of the invention will be more fully disclosed hereinafter, reference being had to the accompanying drawings, of which:

Fig. 1 is a front elevation of my improved depository as it appears after installation in the wall of a building;

Fig. 2 is a rear elevation of the device as it appears before installation;

Fig. 3 is a side elevation having one of the cover plates removed;

Fig. 4 is a vertical longitudinal sectional elevation taken on the line 4—4 of Fig. 1;

Fig. 5 is a sectional plan view taken on the line 5—5 of Fig. 1;

Figs. 6 and 7 are views similar to Figs. 4 and 5, but illustrating the elements of the apparatus in a deposit receiving position;

Fig. 8 is a sectional plan view taken on the line 8—8 of Fig. 4;

Fig. 9 is an enlarged sectional elevation taken on the line 9—9 of Fig. 8, and

Fig. 10 is a perspective view of a detail of the invention.

My improved depository comprises a main housing 1 consisting of a pair of main body sections 2 and 3 respectively, a bottom section 4, a top section 5 and a front section 6. The sections 2 and 3 are respectively provided with vertical rear flanges 7, 7 adapted to receive bolts 8, by means of which the two main sections of the housing are secured together. The sections 2 and 3 are also provided with a circular segmental front flange 9 through which these main sections are secured to the front section 6 by means of bolts 10, 10. The bottom section 4 is also provided with a seg-

mental flange 11 which is secured to the front section 6 by bolts 10, 10, and the top section 5 is likewise provided with a segmental flange 12 secured to the front section 6 by means of bolts 10. The top and bottom sections 4 and 5 respectively are each provided with a circular horizontal flange 13 secured to the sections 2 and 3 by means of bolts 14. The sections 2 and 3 of the main housing 1 are provided with a substantially spherical cavity 15 in which is rotatably mounted a substantially spherical member 16 having its upper and lower sides flattened as illustrated at 17 and 18 respectively. This member will hereinafter be referred to as a spherical segmental member.

Suitable antifriction bearings 19 are provided between the lower face 18 of the spherical segmental member 16 and the upper face 20 of the lower housing section 4. A trunnion 21 extends vertically from the upper face 17 of the spherical segmental member 16 between which and the upper section 5 of the main housing is provided an antifriction bearing 22.

The spherical segmental member 16 is provided with a transversely extending cylindrical bore 23 in which is rotatably mounted a deposit receiving cylinder 24, antifriction bearings 25 and 26 being provided between the respective ends of the cylinder 24 and the spherical segmental member 16.

The cylinder 24 is provided with an aperture 27 adapted to register with an aperture 28 formed in the spherical segmental member 16 between the lower face 18 and the cylindrical bore 23 thereof. The aperture 28 is adapted to register with an opening 29 formed in the upper face 20 of the lower section 4 of the main housing, and constitutes an inlet to a chute 30 which at its lower end communicates with a suitable vault within the bank building.

One end of the cylinder 24 is closed by a wall or head 31 having a segmental tongue 32 formed thereon, which is adapted to register with and slide horizontally in a groove 33 formed in the sections 2 and 3 of the main housing 1, and with a groove 34 formed in a plate 35 which is rotatably mounted in one

side of the main housing section 3. The plate 35 is adapted to be rotated relative to the main housing by means of a bevel gear 36 formed on the side of the plate 35 opposite that having the groove 34 formed therein. The bevel gear 36 meshes with a bevel pinion 37 mounted on one end of a shaft 38 which is rotatably mounted in bearings 39 and 40 formed in a cap section 41, secured to the main housing section 3, by means of bolts 42.

A spur gear 43 is secured to the end of the shaft 38 adjacent the bearing 40, and meshes with a second spur gear 44 mounted on a projection 45 extending from the inner member of a conventional form of barrel lock 46. The inner member of said lock is adapted to be rotated with respect to the outer member thereof by means of a key 47 adapted to be inserted within said inner member and to move the plungers of said lock into an unlocking position. The outer member of the lock 46 is prevented from being rotated by means of a set screw 48 in the front section 6 of the main housing 1. The cap member 41 is closed by means of a cover plate 49, the barrel lock 46 being of a conventional form has not been shown in detail. This lock projects outward from the front section 6 of the main housing 1 through an ornamental circular face plate 50.

The face plate 50 may be secured to the front section 6 of the main housing in any suitable manner, and in the present instance I have illustrated screws 52 which pass through a rearwardly extending circular flange 51, of the face plate 50, into the front section 6 of the main housing.

Within the casing 5, a bevel gear 55 is secured to the upper face 17 of the spherical segmental member 16. The bevel gear 55 meshes with a bevel pinion 56 secured to one end of a shaft 57 mounted in a bearing 58 formed in the said casing 5. The opposite end of the shaft 57 is journaled in the front plate 6 of the main housing. Between the bearing 58 and the front plate 6 a spur gear 59 is secured to the shaft 57 and meshes with a second spur gear 60 mounted on one end of a shaft 61, which is journaled in the front section 6 of the main housing and the face plate 50, and is provided at its opposite end, beyond the face plate 50, with a suitable hand wheel 62.

The spherical segmental member 16 and the cylindrical member 24 are adapted to be moved from their locked or deposit discharging positions illustrated in Figs. 4 and 5 to their unlocked or deposit receiving positions illustrated in Figs. 6 and 7 for the purpose of receiving a deposit. When occupying the positions illustrated in Figs. 6 and 7, the open end of the cylinder 24 registers with a circular opening 65 formed in the face plate 50.

On the upper face 17 of the spherical segmental member 16 is mounted a pin 66 which

is adapted to engage, respectively, pins 67 and 68 which project inwardly from the wall of the casing 5, thereby limiting the movement of the spherical segmental member 16 within the main housing 1.

Pivoted on the upper face 17 of the spherical segmental member 16 is a detent 69, which is adapted to engage a ratchet segment 70 secured to the inner wall of the said casing 5. The pawl 69 is adapted to be moved into engagement with the ratchet segment 70 by means of a flat spring 71, and to be moved out of engagement with said ratchet segment by means of a pin 72 secured in one end of a sliding block 73 mounted in a guideway 74 formed in the upper surface 17 of the spherical segmental member 16. A plate 75 secures the sliding block 73 in place, and is provided with a slot 76 through which the pin 72 extends. The pin 72 engages a projection 72^a on the pawl 69. The opposite end of the sliding block 73 is provided with a downwardly extending pin 77, operable in the slot 78 formed in the spherical segmental member 16 between the guideway 74 of said block, and the cylindrical bore 23 formed in the said spherical segmental member 16. The pin 77 extends into a spiral cam groove 79 formed in the periphery of the cylinder 24 adjacent the head 31 thereof. The pawl 69 is adapted to be held out of engagement with the ratchet segment 70 by means of a catch 80 which is pivoted at 81 to the upper face 17 of the spherical segmental member 16. The catch 80 is provided with a shoulder 82 adapted to engage the point of the pawl 69. A flat spring 83 is secured to the catch 80 at one of its ends and its opposite end is operatively mounted in a vertically extending pin 84 on the upper face 17 of the said spherical segmental member 16. The catch 80 is provided with a projection 85 adapted to be engaged by a pin 98 secured in the inner wall of the casing 5. A pin 100 on the latch 80 engages a stop pin 101 on the face 17 to limit the movement of said latch in one direction.

The tongue 32 of the cylinder 24 is provided at one of its ends with a blade 32^a adapted to enter a slot 86 formed in the wall at one end of the groove 34 in the plate 35. One end 87 of a plunger 88 is also adapted to enter the slot 86 at predetermined intervals. The plunger 88 is slidably mounted in a cavity 89 formed in the section 3 of the main housing 1. A spring 90 is mounted in the cavity 89 between a shoulder 91 on the plunger 88 and a screw plug 92 forming a closure for the said cavity 89.

Under normal conditions the elements of the apparatus assume the positions illustrated in Figs. 4 and 5, and in order to make a deposit the key 47 is inserted in the barrel lock 46. If the key 47 be the proper one for operating the lock, the lock plungers are moved to an inoperative position, and the

inner section of the lock is permitted to be rotated. Upon rotating the key 47, the spur gear 44 is rotated and consequently the gear 43, shaft 38 and bevel pinion 37 are likewise rotated. Rotation of the gear 37 will rotate the gear 36 and the plate 35, the tongue 32 of the cylinder 24, being within the groove 34 of said plate 35, will consequently effect rotation of the cylinder 24 within the spherical segmental member 16, whereby the solid portion of the circular side wall of the cylinder is moved to a position closing the opening 28 in the spherical segmental member 16, and the opening 27 in said cylinder will be moved 10 to the position illustrated in Fig. 6, thus communication between the interior of the cylinder 24 and the chute 30 is cut off. When the cylinder 24 is moved to this closing position, one end of the tongue 32 thereof is 15 brought into operative alignment with the horizontal groove 33 formed in the main housing 1 of the apparatus. The spherical segmental member 16 may then be rotated horizontally within the housing 1 by the bevel gear 20 55, pinion 56, shaft 57, spur gear 59, spur gear 60, shaft 61 and the hand wheel 62.

Upon referring to Fig. 3, it will be noted that the rotation of this spherical segmental member ordinarily is prevented by the end 30 of the tongue 32 engaging the solid wall formed at the end of the slot 34 in the plate 35 which had previously been rotated substantially 176°. Upon rotation of the spherical segmental member 16, the tongue 32 moves out of the groove 34 into the groove 33 of the main housing. The end 87 of the spring plunger 88 follows the blade end 32^a of the tongue 32 and moves into the slot 86 formed in the end wall of said groove 34, preventing rotation of the plate 35 relative 35 to the main housing 1, and thus preventing withdrawal of the key 47 until such time as the tongue 32 again moves into the groove 34 and the blade 32^a engages the end 87 of the plunger 88 moving it outward to the periphery of the plate 35, thus permitting rotation of said plate. Continuing the rotation of the spherical segmental member 16 from the position illustrated in Fig. 5 to the deposit receiving position illustrated in Fig. 7 causes the open end of the cylinder 24 to register with the opening 65 in the face plate 50, the pawl 69 during this movement being held out of engagement with the ratchet segment 70 by means of the catch 80.

Immediately prior to the alignment of the open end of the cylinder 24 with the opening 65, the point 85 of the catch 80 engages the pin 98 in the casing 5 and turns the catch 80 on its pivot 81 to such an extent, as illustrated in Fig. 8, that the pawl 69 is released from the shoulder 82 of the catch 80 and is moved into engagement with the ratchet segment 70 by means of the spring 71.

It will be understood that the previous rotation of the cylinder 24 within the spherical segmental member 16 has caused the pin 72 to be moved to the opposite end of its slot 76 through the co-operative action of the spiral cam groove 78 in said cylinder, and the pin 77 which projects from the sliding block 73 into said cam groove.

The apparatus is now in position to receive a deposit, after which the hand wheel 62 is again rotated, in an opposite direction, and through the train of gears above mentioned rotates the spherical segmental member 16, around its vertical axis within the housing 1, from the position illustrated in Fig. 7 to that 75 illustrated in Fig. 5. During this movement of the spherical segmental member 16, the tongue 32 of the cylinder 24 slides horizontally within the groove 33 formed in the main housing, thus preventing rotation of the cylinder 80 in the spherical segmental member 16, and from there into the groove 34 in the rotatable plate 35. As the tongue 32 approaches the end of its movement within the groove 34, the blade end 32^a of said tongue engages the end 87 of the spring-pressed plunger 88, and moves the same out of the slot 86 into alignment with the periphery of the plate 35.

The cylinder 24 may now be rotated within and relative to the spherical segmental member 16 by turning the key in a direction opposite to that previously described. The opening 27 in said cylinder is then brought into alignment with the opening 28 in the spherical segmental member 16, and the deposit, which has been previously placed on the cylinder 24, is dropped from said cylinder through the opening 28 into the chute 30, through which it passes to the vault. As the spherical segmental member 16 is moved 100 from the deposit receiving position (Fig. 7) to the deposit dumping position (Fig. 5) the pawl 69 engages the teeth of the ratchet segment 70, and thus prevents rotation of the said spherical segmental member in an 105 opposite direction until such time as the deposit therein has been dumped into the chute 30. Release of the pawl 69 is possible only after the cylinder 24 has been rotated to its dumping position wherein the pin 77 traveling in the cam groove 78 in said cylinder moves the slide block 73 and the pin 72 and consequently the pawl 69 to the position shown in Fig. 8, wherein the end of the pawl 69 is moved out of engagement with 110 the ratchet segment 70 and into engagement with the shoulder 82 of the catch 80. The key 47 may then be removed from the lock 46, due to the fact that the plungers of said lock at such time are in operative locking 115 alignment with the other elements of the said barrel lock. The apparatus is then in position to be operated for the reception of another deposit.

The member 16 is adapted to be formed

of hard metal such as tool steel and the outer surface polished to a high degree. Thus when the apparatus is in the position illustrated in Fig. 4, a convexed or spherical surface α is presented to the opening 65 in the face plate 50, which will resist twist drills or any other form of tool or torch employed with a view of gaining access to the chute 30 through the spherical segmental member

16.

10 While I have described my invention as being placed in the outer wall of a bank building, obviously, it may be mounted in any form of safe or vault, portable or otherwise, or any other type of deposit receiving unit, without departing from the essential features of the invention.

I claim:

11 1. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to be moved into registry with the deposit receiving opening in said housing; and having an opening adapted to be moved into registry with the deposit discharge passage in said spherical segmental member.

15 2. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to be moved into registry with the deposit receiving opening in said housing and having an opening adapted to be moved into registry with the deposit discharge passage 20 in said spherical segmental member; means for rotating the cylinder within the oblate spheroid member; and means for rotating the spherical segmental member within the housing.

25 3. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to

be moved into registry with the deposit receiving opening in said housing and having an opening adapted to be moved into registry with the deposit discharge passage in said spherical segmental member; key operated means for rotating the cylinder within the spherical member; and means for rotating the spherical segmental member within the housing.

4. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to be moved into registry with the deposit receiving opening in said housing and having an opening adapted to be moved into registry with the deposit discharge passage in said spherical segmental member; key operated means for rotating the cylinder within the spherical segmental member; and means including a hand wheel for rotating the spherical segmental member within the housing, independent of and subsequent to the rotation of said cylinder by said key operated means.

5. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to be moved into registry with the deposit receiving opening in said housing and having an opening adapted to be moved into registry with the deposit discharge passage in said spherical segmental member; means for rotating the cylinder within the spherical segmental member; means for rotating the spherical segmental member within the housing; and means for locking the spherical segmental member against rotation relative to said housing when the said cylinder is in a discharging position.

6. In a depository apparatus, the combination of a housing having a deposit receiving opening in one side thereof and a deposit discharge opening in another side thereof; with a spherical segmental member rotatably mounted in said housing having a cylindrical cavity and a passage in said spherical member communicating with said cylindrical cavity and adapted to register with said deposit discharge opening in said housing.

deposit discharge opening in said housing; a hollow cylinder rotatably mounted in said cylindrical cavity adapted to be moved into registry with the deposit receiving opening in said housing and having an opening adapted to be moved into registry with the deposit discharge passage in said spherical segmental member; means for rotating the cylinder within the spherical segmental member; means for rotating the spherical segmental member within the housing; and means for preventing rotation of the cylinder relative to the spherical segmental member when said cylinder is in the deposit receiving position in registry with the deposit receiving opening in said housing.

7. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to be moved into registry with the deposit receiving opening in said housing and having an opening adapted to be moved into registry with the deposit discharge passage in said spherical segmental member; means for rotating the cylinder within the spherical segmental member; means for rotating the spherical segmental member within the housing; means for locking the spherical segmental member against rotation relative to said housing when the said cylinder is in a discharging position; and key operated means for locking said cylinder in said discharging position.

8. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to be moved into registry with the deposit receiving opening in said housing and having an opening adapted to be moved into registry with the deposit discharge passage in said spherical segmental member; means for rotating the cylinder within the spherical segmental member; means for rotating the spherical segmental member within the housing from a deposit discharging position to a deposit receiving position and vice versa; and means for preventing a reverse rotation of the said spherical segmental member, while the same is moving toward the said discharge

position from the deposit receiving position thereof.

9. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to be moved into registry with the deposit receiving opening in said housing and having an opening adapted to be moved into registry with the deposit discharge passage in said spherical segmental member; means for rotating the cylinder within the spherical segmental member; means for rotating the spherical segmental member within the housing from a deposit discharging position to a deposit receiving position and vice versa; means for preventing a reverse rotation of the said spherical segmental member, while the same is moving toward the said discharge position from the deposit receiving position thereof; and means operable by said cylinder for controlling said reverse preventing means.

10. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to be moved into registry with the deposit receiving opening in said housing and having an opening adapted to be moved into registry with the deposit discharge passage in said spherical segmental member; means for rotating the cylinder within the spherical segmental member; means for rotating the spherical segmental member within the housing from a deposit discharging position to a deposit receiving position and vice versa; means for preventing a reverse rotation of the said spherical segmental member, while the same is moving toward the said discharge position from the deposit receiving position thereof; means operable by said cylinder for releasing said reverse preventing means when said cylinder is moved within said spherical segmental member to its deposit discharging position; and means for automatically resetting said reverse preventing means when said spherical segmental member is moved to its deposit receiving position.

11. In a depository apparatus, the combination of a housing having a deposit receiving opening in one side thereof and a de-

posit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity having an open end adapted to be moved into registry with the deposit receiving opening in said housing and having an opening adapted to be moved into registry with the deposit discharge passage in said spherical segmental member; means for rotating the spherical segmental member within the housing; a tongue on one end of said cylinder; a plate rotatably mounted in said housing and having a groove adapted to receive said tongue; said housing also having a groove adapted to receive said tongue; and key operated mechanism for rotating said plate to a position wherein the groove of said plate is out of cooperative alignment with the groove of said housing for locking the spherical segmental member against rotation relative to said housing when the said cylinder is in its discharging position.

12. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity adapted to be moved into registry with the deposit receiving opening in said housing and having an opening adapted to be moved into registry with the deposit discharge passage in said spherical segmental member; means for rotating the cylinder within the spherical segmental member; and means for rotating the spherical segmental member within the housing, comprising a hand wheel outside said casing and secured to one end of a shaft which extends into said housing; a second shaft journaled in said housing; spur gears cooperatively connecting said shafts; a bevel gear on the end of said second shaft and meshing with a bevel gear secured to said spherical segmental member.

13. In a depository apparatus, the combination of a housing having a deposit receiving opening in one side thereof and a deposit discharge opening in another side thereof; with a spherical segmental member rotatably mounted in said housing having a cylindrical cavity and a passage communicating with said cylindrical cavity and adapted to register with said deposit discharge opening in said housing; a hollow cylinder rotatably mounted in said cylindrical cavity

adapted to be moved into registry with the deposit receiving opening in said housing and having an opening adapted to be moved into registry with the deposit discharge passage in said spherical segmental member; means for rotating the cylinder within the spherical segmental member; means for rotating the spherical segmental member within the housing from a deposit discharging position to a deposit receiving position and vice versa; a pawl pivoted to said spherical segmental member adapted to engage a ratchet segment in said housing for preventing a reverse rotation of the said spherical segmental member, while the same is moving toward the said discharge position from the deposit receiving position thereof; a block slidably mounted in said spherical segmental member and having a pin engaging said pawl; a second pin on said slide block projecting into a cam groove formed in said cylinder for releasing said pawl from said ratchet when said cylinder is moved within said spherical segmental member to its deposit discharging position; a latch for maintaining said pawl in its released position; and a pin in said housing adapted to engage said latch for automatically resetting said pawl when said spherical segmental member is moved to its deposit receiving position.

14. In a depository apparatus, the combination of a housing having a deposit receiving opening in one side thereof and a deposit discharge opening in another side thereof; with a spherical segmental member rotatably mounted in said housing and provided with a deposit receiving cavity having an open end adapted to register with the deposit receiving opening in said housing and a passage communicating with said deposit receiving cavity and adapted to register with said deposit discharge opening in said housing; means movable with respect to said housing and with respect to the spherical segmental member for closing the passage between said deposit receiving cavity and the passage communicating with said deposit discharge opening when the deposit receiving cavity of said spherical segmental member is in registry with the deposit receiving opening in said housing.

JAMES R. JOHNSTON.
